(57) **CLAIM**

The ornamental design for a cover for cancer cell observation camera, as shown and described.

DESCRIPTION

FIG. 1 is a front view of a cover for cancer cell observation camera of the present invention.

FIG. 2 is a rear view of the cover for cancer cell observation camera of FIG. 1.

FIG. 3 is a top plan view of the cover for cancer cell observation camera of FIG. 1.

FIG. 4 is a bottom plan view of the cover for cancer cell observation camera of FIG. 1.

FIG. 5 is a right side view of the cover for cancer cell observation camera of FIG. 1.

FIG. 6 is a left side view of the cover for cancer cell observation camera of FIG. 1.

FIG. 7 is a perspective view showing the top of the cover for cancer cell observation camera of FIG. 1.

FIG. 8 is a perspective view showing the bottom of the cover for cancer cell observation camera of FIG. 1.

FIG. 9 is a sectional view taken along line 9-9 of FIG. 1.

FIG. 10 is an enlarged view showing a portion of FIG. 9 defined by line 10-10.

FIG. 11 is an enlarged view showing a portion of FIG. 4 defined by lines 11-11.

FIG. 12 is a perspective view showing the bottom of the cover for cancer cell observation camera of FIG. 1 in a state of use; and,

FIG. 13 is a perspective view showing the top of the cover for cancer cell observation camera of FIG. 1 in a state of use. The evenly-dashed broken lines in the drawings illustrate the portions of the design that form no part of the claim. The dot-dash broken lines in the drawings represent the bounds of the claimed subject matter, the dot-dash lines, themselves forming no part thereof.
